ATTACHMENT FOR AIR LINES

Fred I. Jaden and Arthur B. Arnold,
Hastings, Nebr.

Application November 17, 1933, Serial No. 698,516

6 Claims. (Cl. 299—88)

This invention relates to attachments for air lines and air brushes; and, more particularly, attachments adapted to be used in connection with what is commonly known as a "Schrader chuck".

5 Air brushes of necessity must have a source of compressed air, and it is obvious that if the standard air line commonly found around garages and filling stations could be used, a great deal of complicated mechanism would be obviated. 10 We have devised an attachment which receives the "Schrader chuck" and permits the controlled operation of the same without dismembering any part of the apparatus.

The prime object of our invention is to provide 15 an attachment for air brushes and the like adapted to receive an air chuck and permit manual operation of the same so that a source of air pressure is provided for the brush. Due to the peculiar construction of the air chuck, which is 20 designed to fit over the valve of a tire and be operated by said valve, the attachment must be so constructed as to readily receive the chuck, and at the same time, apparatus much be provided for operating the valve in the chuck.

25 Another object of the invention is to provide means for controlling the pressure since the ordinary air line around the filling station is capable of furnishing air under pressure up to one hundred pounds and such pressure is not always desired in connection with an air brush.

Another object is to provide a quick detachable connection between the air line attachment and the air brush, air cleaning apparatus and other devices requiring air pressure. Other objects will be disclosed in the specification and 30 claims forming a part hereof.

In the drawings:

Figure 1 is a side elevation, partly broken away in section, showing the air brush attached in operative position to the "Schrader chuck";

Figure 2 is a perspective of the attachment;

Figure 3 is a front elevation of the nozzle of the air brush;

Figure 4 is a vertical section of a modified form 45 of attachment;

Figure 5 is a front perspective of the modified form shown in Figure 4.

Figure 6 is a side elevation, partly broken away in section, of still another modified form of connection between the air brush and attachment;

Figure 7 is a side elevation, partly broken away in section, of the bayonet joint connection of a modified form; and

Figure 8 is a vertical section taken on line 8—8 55 of Figure 7.

Referring to the drawings, in which similar parts are designated by like numerals:

Numeral 4 designates an air line having an air chuck 5 at the end thereof. Numeral 6 represents a bent tube, preferably of brass or steel, of a 60 diameter adapted to fit into the chuck 5 and surround the chuck valve 7. Secured to the bent tube 6 by welding, or by other means, is a resilient flat strip 8 having a cup portion 9 adapted to receive the chuck 5 and fork members 10 in the form of a yoke designed to receive the neck portion 11 of the chuck 5. A second strip 12 is welded, or otherwise secured, to the strip 8 and bent upwardly to surround the tube 6 through an opening 13, a collar 14 being 70 swedged in the opening 13 so as to slide on the tube 6. The end 15 of the tube 6 is threaded to a nut 16 which has a flat piece of spring steel 17 extending therefrom and secured thereto. The end 18 of the spring steel 17 is slotted at 75 19 and turned up to receive a threaded projection 20 extending from the air brush 21. The threaded projection 20 forms a part of the attachment and can be screwed into various apparatus besides an air brush. Such apparatus will be provided with a threaded hollow end adapted to receive the threaded projection 20. Two hexagon nuts 22 are adapted to be threaded on the projection 20 after the projection 20 has been placed in the slotted member 19, the spherical end 23 of 80 the threaded projection 20 riding in spherical seat 24 formed in the nut 16. The threaded projection 20 is hollow and is threadedly connected to the air brush 21 at 25 in alignment with a passage 26 extending through the air brush 21. 90 The outer hexagon nut 22 has an oval face adapted to fit into the slotted member 19, the other nut 22 serving to lock the same in place.

A paint tube 33' extends through a nozzle 40 and aligns with a passage 33 which extends 95 through the lower portion of the air brush. A glass receptacle 35 is connected to the air brush 21 by a screw cap 37. Extending into the glass receptacle 35 is a tube 36 which connects with the passage 33. The nozzle 40 is screwthreaded 100 to the air brush 21 leaving a central opening 34 through which the paint tube 33' extends.

Two openings 38 and 39 are formed at an angle to each other in the face of the nozzle 40, the face of the nozzle being concave so as to form a slight vacuum as the air is forced out through the openings 34, 38 and 39, and cause the paint to be sucked from the jar 35 and discharged through the paint tube 33', the air and paint mixing in the form of a flat spray. A valve 41, 110

similar to screw valve 29, controls the paint passage 33. The screw head 30 can be adjusted so as to control the amount of air passing through the passage 27 so that different mixtures and different pressures may be obtained.

As will be evident from Figure 1, the face of the nut 22 adjacent the slotted end 18 of the spring 17 is rounded off so as to slide easily against the furcations of said end. The outer 10 nut constitutes a shoulder or flange on the threaded projection 20, which may be adjusted to insure a yielding pressure by the end 18 sufficient to force the spherical end of projection 20 into air-tight contact with the spherical seat 15 24 formed in the nut 16.

The handle member shown in Figure 2 is obviously intended as a connection which may be "snapped" at its opposite ends on to fittings, one of which is the standard tire chuck of an air 20 compressor pipe, while the other is a special fitting adapted to be connected to any standard spray gun. The connection and disconnection of this handle with respect to the fittings at its opposite ends can be effected almost instantly 25 and without the use of tools of any kind.

The modified forms as shown in Figures 4 and 5 differ from the preferred form in that the spring steel member 17 is lighter and includes a nut 42 placed on the threaded projection 20 between the air brush 21 and the slotted end 18, which serves 30 to prevent accidental displacement. The nut 42 can be tightened against the face of the turned-up slotted end 19 so as to securely hold the connection in place, and can readily be unscrewed 35 when it is desired to use some form of attachment other than the air brush.

The modified form as shown in Figure 6 differs from the preferred form in that a coupling 43 connects the end 15 of the bent tube 6 to a connection 44 having a shoulder 45 freely revolvable in a union nut 46 which in turn is threadedly connected to the threaded projection 20. Packing in the form of a washer 47 is placed 40 between the connection 44 and the end of the projection 20. This permits the air brush to be freely turnable without twisting the air line.

Figure 7 shows a modified form of connection in the form of a bayonet slot. A sleeve 48 is screwthreaded to the end 15 of bent tube 6 and the bayonet slot 49 is formed in the opposite end 50 adapted to receive a pin 50 formed on the projection 20 in lieu of the threads shown in the preferred form. A rubber packing 51 is used to form a seat and seal for the joint.

As actually used in the preferred form, the chuck is inserted in the cup portion 9, the fork members 10 encircling the neck 11 of the chuck 5, the bent tube 6 surrounding the check valve 7. The bent tube 6 and the strip 8 are grasped and 55 pressure exerted on the resilient strip 8 which forces the collar 14 upon the tube 6 bringing the chuck 5 and in turn the check valve 7 into contact with the end of the tube 6 so that air from the air line 4 will pass through the bent tube 6 and in turn through the air brush 21. The flow 60 of air can be regulated by way of the valve 29, regardless of the pressure in the air line 4. As the air passes through the openings 34, 38 and 39 in the nozzle 40, a partial vacuum is created 65 due to the concave face of the nozzle 40, and the fact that the openings in the nozzle are larger than the openings in the paint tube 33, and paint or other material is sucked up through the tubes 36 and 33 and discharged into the flow of 70

air. The flow of paint can be controlled by way of the valve 41.

If it is desired to substitute some other apparatus for the air brush, it is only necessary to loosen the nut 42 so that it no longer exerts pressure on the slotted members 19 of the spring steel member 17. The threaded projection 20 may then readily be removed and a new piece of apparatus substituted. Of course, upon pressure being released against the resilient strip 8, the chuck 5 will be drawn away from the end of the bent tube 6 and the valve 7 in the chuck will close.

The use of the apparatus is exactly the same in the modified forms shown in Figures 4, 5, 6, 7 and 8, the modifications being directed to the connections between the air brush and the "Schrader chuck" attachment.

It is obvious that our invention is not limited to be used with an air brush per se, as apparatus for cleaning greasy parts with kerosene or removing dust by air pressure, and many other devices, may be substituted for the air brush.

Numerous variations may doubtless be devised by persons skilled in the art without departing from the principles of our invention. We, therefore, desire no limitations to be imposed on our invention, except such as are indicated in the appended claims.

What we claim is:

1. The combination of a valve controlled source of fluid with a valve casing, an inwardly opening valve and a valve line, a tube having one end bent, a resilient strip supported by said tube and bent to a substantial parallel plane with the major portion of said tube and having a supporting member formed at the end thereof in line with said downturned portion of said tube, a guide member secured to said resilient strip and bent to be spaced from said supporting member, the end of said guide member having an opening therein through which the bent portion of said tube is freely slidable, said valve casing being supported by said supporting member with said valve in position to be operated by movement of said bent portion in said opening, and resilient clamping means extending from the other end of said tube and adapted to be sprung into and out of operative connection with a spray gun.

2. The combination of a valve controlled source of fluid with a valve casing, an inwardly opening valve and a valve line, a tube having one end bent, a resilient strip secured to said tube and bent to a substantial parallel plane with the major portion of said tube and having a supporting member formed at the end thereof in line with said downturned portion of said tube, a guide member secured at one end to said resilient strip and bent to have its other end spaced from said supporting member, the said other end having an opening through which the bent portion of said tube is freely slidable, said valve and casing being supported by said supporting member with the valve in position to be operated by sliding movement of the said bent portion in said opening.

3. The combination with a spray gun having a passageway for air extending therethrough, a pipe projecting from said gun and communicating with said passageway, a flange on said pipe, an air compressor pipe having a tire chuck at the end thereof, a handle including an air tube, means at one end of said handle for clamping the tire chuck against one end of said tube, and means at the other end of the tube cooperating

with said flange for clamping said other end against the end of said projecting pipe, said handle including parts relatively movable to operate said tire chuck.

- 5 4. The combination with a spray gun having a pipe projecting therefrom in alignment with an air passageway extending through said gun, of an air compressor pipe having a tire chuck controlling the flow of air therefrom, a handle 10 comprising relatively movable parts including a tube, and yielding means at the opposite ends of said tube adapted to be "snapped" on to said pipe and tire chuck to establish communication through said tube between said pipe and chuck, 15 said handle being operable by movement of said parts toward each other to operate said chuck.
5. A handle for a spray gun comprising a pipe 20 adapted to be connected to a spray gun in communication with an air passageway extending through the gun, a handle including an air tube, and resilient means at opposite ends of said tube

adapted to be "snapped" into operative engagement with said pipe and the tire chuck of an air compressor pipe, the resilient means engaging the tire chuck being movable toward said tube to operate the air valve in said chuck.

6. A handle construction for an air spray gun of the type having an air conduit, comprising an open ended air tube having a coupling at one end adapted to connect it to the air conduit of said spray gun, the opposite end being adapted to be placed into communication with the chuck of an air hose, a hand hold carried by said air tube, said hand hold including a seat for an air hose chuck of the type having a normally closed check valve, said tube and said hand hold being relatively movable for bringing said opposite end of said air tube into communication with and into valve opening relation to the air chuck.
